United States Patent Office.

AMOS H. RHODES, OF FALL RIVER, MASSACHUSETTS.

Letters Patent No. 78,761, dated June 9, 1868.

IMPROVEMENT IN GIBS.

The Schedule referred to in these Letters Patent and making part of the same.

TO ALL WHOM IT MAY CONCERN:

Be it known that I, AMOS H. RHODES, of Fall River, in the county of Bristol, in the State of Massachusetts, have invented a new and useful Improvement in a "Gib" for a Steam-Engine; and I do hereby declare that the following is a full and exact description thereof, reference being had to the accompanying drawings, and to the letters of reference marked thereon.

My invention consists in forming a recess in the "gib," and fitting therein a metallic block, and securing it to the "gib" with bolts, screws, or shoulders.

Figure 1 is a perspective view of a "gib," with my invention applied to it.

Figure 2 is a top view of fig. 1, with block B' removed.

Fig. 1. A¹ is the "gib;" B¹, the metal block; C¹, the nut in which the cross-head stud is secured. On the under side of this nut is a projection, shown by C², which projection is as deep as the thickness of the block B¹. D¹ is the bolt which secures the block B¹ to A¹. E¹ is an adjusting-bolt, to adjust the block B¹ to the nut C¹. F¹ is the Babbitt face of the "gib."

Fig. 2. A² is the "gib;" G², the recess for metal block; d is hole for bolt D¹; B², metal block, removed from fig. 2 and reversed; a², slot through which D¹ passes; C², nut reversed; D² and E², bolts and washers removed from fig. 1; c, hole through which bolt E² passes.

Operation.

In the well-known manner of securing the "cross-head stud" to the "gib," there is no way of removing the "gib" to supply a duplicate but by removing the cylinder-head from the cylinder, the piston-rod from the piston, disconnecting the piston-rod and the sweep, and sliding the "gib" out of the guides. By removing the metal block B¹, the "gib" may be easily and quickly removed, and a duplicate applied in its place, as will be observed, without further specification.

Claim.

What I claim as my invention, and desire to secure by Letters Patent, is—

The construction and arrangement of "gib" A¹, removable block B¹, and bolts D¹ and E¹, operating substantially as and for the purpose set forth and described.

AMOS H. RHODES.
